[57] CLAIM

The ornamental design for a combined topical composition dispenser/applicator and cap, as shown and described.

DESCRIPTION

FIG. 1 is a perspective view of our new design of a combined topical composition dispenser/applicator and cap; FIG. 2 is a front elevational view thereof, the undisclosed rear elevational view being a mirror image;

FIG. 3 is a side elevational view thereof, the undisclosed opposite side being a mirror image;

FIG. 4 is a top plan view thereof;

FIG. 5 is a bottom plan view thereof;

FIG. 6 is an exploded front elevational view of the dispenser/applicator and cap illustrated in FIG. 2;

FIG. 7 is a top plan view of the dispenser/applicator thereof;

FIG. 8 is a bottom plan view of the cap thereof;

FIG. 9 is a perspective view of a modified embodiment of that illustrated in FIG. 1;

FIG. 10 is a front elevational view of the embodiment of FIG. 9, the undisclosed rear elevational view being a mirror image;

FIG. 11 is a side elevational view thereof, the undisclosed opposite side being a mirror image;

FIG. 12 is a top plan view thereof;

FIG. 13 is a bottom plan view thereof;

FIG. 14 is an exploded front elevational view of the modified dispenser/applicator and cap illustrated in FIG. 10;

FIG. 15 is a top plan view of the dispenser/applicator thereof;

FIG. 16 is a bottom plan view of the cap thereof; and,

FIG. 17 is a front elevational view of a modified embodiment of that illustrated in FIGS. 1 and 9.
